UNITED STATES PATENT OFFICE

DEAN M. SOLENBERGER, OF CLEVELAND, OHIO, ASSIGNOR TO THE SIMPLEX PISTON RING COMPANY OF AMERICA, INC., A CORPORATION OF OHIO

PISTON RING

Application filed September 26, 1927. Serial No. 222,092.

The invention relates to piston rings of that type circumferentially slotted for axial resiliency and the invention consists in the novel construction as hereinafter set forth.

5 In the drawings;

Figure 1 is a section through a portion of the piston provided with three ring grooves showing my improved construction of ring in the lower groove.

10 Figure 2 is a side elevation of a portion of the ring.

Figure 3 is a cross section thereof.

Figure 4 is a view similar to Figure 2 showing a modification.

15 In the manufacture of circumferentially slotted rings it is usual to form the slots as narrow as possible. It is of course, necessary that the slotting saws should be of sufficient gauge or strength to perform the work and 20 it is also necessary to remove sufficient material for the axial contraction of the ring through which the axially expansible tension is developed. However, both of these effects may be produced by the use of comparatively 25 narrow gauge saws.

It is the primary object of the present invention to obtain a ring which will have increased efficiency in barring the passage of oil or, what is commonly known as oil pumping.

30 This I have accomplished by increasing the width of the slots so as to first reduce the peripheral contact area of the ring and second, provide wider passages for the oil through the ring into the groove.

35 As shown A is the piston having three ring grooves therein, B, B', B² the groove B² being provided with drain apertures C through the piston wall. D is an ordinary solid section ring occupying the upper

40 groove B. E is a circumferentially slotted and axially resilient ring occupying the second groove with a corrugated ribbon expander F for assisting in radial expansion and G a ring of my improved construction 45 occupying the groove B².

As clearly shown in Figure 1 one of the slots in the ring G is much greater in width than the slots in the ring E and consequently the area of peripheral contact may be determined by specific conditions and is entirely independent

of the factor of axial tension. This is for the reason that the axial tension is produced by the deflection only of that portion G' of the ring between the upper slots G² and the lower slots G³ and is not materially affected 55 by the width of the portions G⁴ and G⁵ respectively above the slot G² and below the slot G³. Furthermore the axial tension is determined not only by the width of the portion G' but also by its length between the un-slotted portions G⁶ and G⁷ at opposite ends thereof. Thus in designing the ring axial tension and the respective open and closed 60 peripheral areas may be independently chosen.

It is very important in designing a slotted ring to guard against the possibility of bending any portion thereof beyond the elastic limit which would result in breakage. With the construction of the ring E which has comparatively narrow slots the amount of flexing permitted to the intermediate bars remains within safe limits but with wide slots as indicated at G² there would be danger. I have, however, avoided this difficulty by making the lower slots G³ narrow so that axial pressure applied to the ring cannot compress it far enough to overstress the bars G'.

With the modified construction shown in Figure 4 the ring H has both the upper slot H' and lower slot H² of considerable width. I have however, avoided overstressing of the intermediate bar H³ by the provision of stops H⁴ in each of said slots which limit the amount of axial contraction.

As shown in Figure 1 the ring G has its upper portion reduced in radial depth while its lower portion is provided with an inwardly extending flange H⁵ to increase the land contact on the lower face of the ring groove. 90 The ring is also provided with a corrugated ribbon expander J of a width less than that of the ring and held from displacement by the flange H⁵. This construction is particularly useful in connection with the cylinders which are distorted or non-circular as the increased flexibility of the ring together with the distributed radial pressure of the expander permits of conforming to such distortions. On the other hand for many purposes the ring 100

may be constructed as shown in Figure 3 where it is of full radial depth and depends upon its own resiliency for radial expansion.

In operation the ring in sliding over the oiled surface of the cylinder wall will permit the passage of oil inward through the slots while the restricted area of peripheral contact under the radial expansive pressure tends to thin the oil film and to prevent its passage into the combustion chamber. The upper and lower slots being staggered in relation to each other provides all portions of the ring with at least one slot thereby avoiding leakage of the lubricant by the ring at any point.

10 15 What I claim as my invention is:

1. A piston ring slotted for axial resiliency and for the passage of lubricant inward therethrough the width of some of said slots being greater than the permissible axial contraction of the ring and means for preventing collapsing of the ring beyond said permissible limit.

2. A piston ring of a normal width greater than the ring groove circumferentially slotted for axial resiliency and for the passage of lubricant therethrough, said slots being arranged in staggered series to produce flexible bars therebetween, the slots of one series being limited in width to limit the flexing of said bars and the slots of the other series being of greater width to increase the oil passage and to diminish the area of peripheral contact.

In testimony whereof I affix my signature.

DEAN M. SOLENBERGER.
